UNITED STATES PATENT OFFICE.

SEBASTIANO GRASSI, OF RIDGEFIELD, CONNECTICUT.

MILL.

1,269,424.

Specification of Letters Patent. Patented June 11, 1918.

Application filed July 19, 1917. Serial No. 181,469.

To all whom it may concern:

Be it known that I, SEBASTIANO GRASSI, a citizen of the United States, and a resident of Ridgefield, in the county of Fairfield and State of Connecticut, have invented certain new and useful Improvements in Mills, of which the following is a specification.

My improvements relate to apparatus for the grinding of corn, oats, and other raw material which it is desired to reduce to pulverized form,—the invention consisting in the specific construction and arrangement of parts herein described and claimed, a distinctive feature being the mounting of a plurality of peripherally and spirally grooved rolls on the main grinding cylinder, as hereinafter fully set forth.

In the accompanying drawings,

Figure 1, is a side elevation of my versatile farm mill;

Fig. 2, is an isometrical view of a feed box used in connection therewith;

Fig. 3, a central vertical sectional elevation of the apparatus as set for grinding corn, oats or other grain;

Figs. 4, and 5, are detail views of the grain grinding roll;

Fig. 6, a detail view of one of the spirally grooved rollers used in the grain grinding roll.

f, f, represent the frame work of the apparatus supporting what may be designated as the table *f'*, and the shelf *f''*. Interposed between the table *f'*, and the shelf *f''*, and rigidly secured to both is the casing *h*, in which are housed the main crushing roll *C'*, and the reducing rolls *r', r''*. These rolls are mounted on shafts *r³, r⁴*, suitably journaled in the casing *h*. *D*, is a driving shaft mounted in suitable bearings on the shelf member *f''*, and provided with a balance fly wheel *d*, which may also be used as a belt pulley if it is desired to drive the apparatus by auxiliary power instead of manually, for which latter purpose a crank *d'* is provided.

In the arrangement shown in the drawings the crank handle *d'*, is attached directly to the driving gear *d²*, which meshes with a pinion *r⁵*, on the protuberant end of the roll shaft *r²*, thereby driving the roll *r⁴*, in the direction indicated by arrows in the

longitudinal section Fig. 3. The other reducing roll *r'*, is driven in the opposite direction by reason of the peripheral engagement of its teeth with those on the reducing roll *r²*.

The main crushing roll *C'*, is driven by the gear *d²*, by reason of the engagement of said gear *d²*, with the pinion *c'*, secured to the protuberant end of the shaft *e*, on which said main crushing roll *C'*, is mounted.

B, is a feed box which may be used in connection with the hopper member *A*, it being formed with convergent sides and bottom which pass the material to the exit opening *b*, provided with a spring door *b'*, which controls the discharge of material into the feed passage *a*, of the hopper member *A*.

T, is a tub or other suitable receptacle for receiving the crushed material from the chute *h'*, which forms the lower part of the casing *h*, and by means of which ground pomace may be transferred to the strainer *S*, in which it is pressed by means of a follower *P*, actuated by a screw *p*, engaging with a stationary nut *N*, affixed to the frame work.

When grain is to be ground as corn, oats, or in fact any material which it is desired to reduce to pulverized form, the crushing roll *C'*, shown in Figs. 3 to 6, inclusive, is formed with a plurality of equidistant recesses or pockets *c²*, in which are mounted spirally grooved rollers *c³, c⁴*, which act in conjunction with the corrugated surface *h²*, of the casing *h*, to reduce the grain to an impalpable powder,—the rollers *c³*, rolling along said corrugated surface *h²*, so that they rotate in a direction opposite to that of the rotation of the cylinder *C'*, in which they are mounted, and hence retard the passage of the material over said corrugated surface *h²*, in such manner as to subject it to a maximum of attritive action in which the edges of the peripheral spiral grooves of the rollers *c³*, perform an important part. The pulverized material passes out through the reducing rolls *r', r''*, which insure perfect uniformity of product.

What I claim as my invention and desire to secure by Letters Patent is,

In apparatus of the character designated, in combination, a suitable frame, a roll casing supported thereon, and formed with a corrugated attritive surface, a hopper member arranged to feed reducible material to said roll casing, a grinding roll in said casing carrying mounted therein a plurality of

peripherally and spirally grooved grinding rolls, and means for rotating said grinding roll, for the purpose described. 10

SEBASTIANO GRASSI.
